ATTORNEYS

UNITED STATES PATENT OFFICE.

OWEN J. WILLIAMS, OF ORCHARD PARK, NEW YORK.

SOCKET-WRENCH.

1,390,738.

Specification of Letters Patent. Patented Sept. 13, 1921.

Application filed September 14, 1920. Serial No. 410,148.

To all whom it may concern:

Be it known that I, OWEN J. WILLIAMS, a citizen of the United States, and a resident of Orchard Park, county of Erie, and 5 State of New York, have invented a new and Improved Socket-Wrench, of which the following is a full, clear, and exact description.

This invention relates to improvements in 10 socket wrenches, an object of the invention being to provide a socket wrench having radially adjustable jaws, which permits the wrench to accommodate itself to nuts of various sizes.

15 A further object is to provide improved means for radially adjusting the jaws of a socket wrench, and to provide an adjusting mechanism which will be strong and durable, and not readily damaged in the ordinary course of usage.

20 A still further object is to provide a wrench which will be comparatively inexpensive to manufacture and yet will efficiently perform the functions for which it 25 is intended.

With these and other objects in view, the invention consists in certain novel features of construction and combinations and arrangements of parts as will be more fully 30 hereinafter described and pointed out in the claims.

In the accompanying drawings—

Figure 1 represents a view in side elevation of the wrench adjusted to accommodate a small sized nut.

Fig. 2 is a view in longitudinal section on the line 2—2 of Fig. 1.

Fig. 3 is a similar view showing the jaws expanded to receive a large sized nut.

40 Fig. 4 is a top plan view of Fig. 1.

Fig. 5 is a bottom plan view of Fig. 1.

Fig. 6 is a view in transverse section on the line 6—6 of Fig. 2.

Fig. 7 is a plan view of the spring.

45 Fig. 8 is a view in section on the line 8—8 of Fig. 3.

Fig. 9 is a bottom plan view of Fig. 3.

Referring in detail to the drawings, 1 represents the hollow casing of my improved wrench. The casing is cylindrical 50 in cross section with a reduced angular end 2 which is adapted to receive any preferred form of handle, or operating member. The lower edge of the casing is beveled as 55 shown at 3, and provided with a plurality of beveled recesses 4 spaced at equal dis-

tances apart. The walls of these recesses form in effect cam faces. The upper end of the casing 1 is internally screw threaded as shown at 5, and accommodates a threaded shank 6. The shank 6 is formed with a reduced portion 7 below the threads, and below the reduced portion 7, the shank is made with an enlargement 8 forming an annular shoulder 9 around the shank. 60

The angular jaws 10 of the wrench correspond in number to the number of recesses 4, and each jaw is provided with a lug 11 fitting one of the recesses. These jaws are arranged in an annular series forming a 70 socket and any desired number of jaws may be employed in accordance with the shape of the nut to be turned.

Adjacent their upper inner ends, the jaws 10 are provided with inwardly projecting 75 shoulders 12 engaging the shoulder 9 on the shank 6. The jaws form in effect levers which are fulcrumed on the shoulder 9 of the shank. Any suitable number of beveled faces such as 15 constitute the inner walls of 80 the jaws. The outer faces of the jaws preferably correspond to the curvature of the casing 1.

The enlargement 8 on the shank 6 is annularly recessed or grooved at 13 to accommodate a spring 14 which normally engages inner angular faces 15 of the jaws tending to spread the jaws apart and at all times 85 maintaining the lugs 11 in the recesses.

The shank 6 at its upper end is made with 90 a groove 16 to accommodate any suitable tool for turning or adjusting the bolt.

The operation will be readily understood. When the shank 6 is in the position illustrated in Fig. 2, the lugs 11 are engaged by 95 the cam faces within the recesses 4, and the jaws are in position to form the smallest possible socket, the outer ends of the jaws being forced toward their common center against the action of the spring 14. Fig. 100 2 illustrates a bolt head gripped by the jaws when they are in this position. In order to expand the jaws for the accommodation of a larger bolt head, such as that shown in Fig. 3, the shank 6 is moved outwardly allowing the spring 14 to expand the jaws, the jaws fulcruming on the shoulder 9 and spreading apart at their lower ends. 105

It will thus be seen that the jaws are capable of positive radial adjustment in each direction so that they form sockets to accommodate various sizes of nuts. It is also 110

apparent that the socket need not be of hexagonal shape illustrated but would be equally useful and operate on the same principle if made in other angular shapes.

5 While I have illustrated one of the preferred embodiments of my invention, it is obvious that various slight changes and alterations might be made in the general form of the parts described without departing 10 from my invention, and hence I do not wish to limit myself to the precise details set forth, but consider myself at liberty to make such alterations and changes as fairly fall within the spirit and scope of the appended 15 claims.

Having thus described my invention, I claim as new and desire to secure by Letters Patent:

1. A socket wrench, comprising a casing 20 including a threaded portion adjacent its inner end and having an annular series of recesses in its outer end, the walls of said recesses being beveled to form cam faces, a threaded rod screwed into the casing, said 25 rod including an annular reduced portion forming a shoulder, an annular series of jaws fulcrumed on the shoulder and co-operating to form a socket, beveled lugs on the jaws fitting the recesses and engaging the 30 cam faces, and a star spring carried by the rod engaging the inner faces of the jaws and tending to spread them apart.

2. A socket wrench, comprising a casing including a threaded portion adjacent its 35 inner end and having an annular series of recesses in its outer end, the walls of said

recesses being beveled to form cam faces, a threaded rod screwed into the casing, said rod including an annular reduced portion 40 forming a shoulder, an annular series of jaws fulcrumed on the shoulder and co-operating to form a socket, beveled lugs on the jaws fitting the recesses and engaging the cam faces, an annular groove around the lower end of the rod, a star spring located 45 in the groove and including a plurality of radially extending tongues engaging the inner faces of the jaws, and tending to spread them apart.

3. A socket wrench, comprising a casing 50 including a threaded portion adjacent its inner end and having an annular series of recesses in its outer end, the walls of said recesses being beveled to form cam faces, a threaded rod screwed into the casing, said 55 rod including an annular reduced portion forming a shoulder, an annular series of jaws fulcrumed on the shoulder and co-operating to form a socket, beveled lugs on the jaws fitting the recesses and engaging the 60 cam faces, an annular groove around the lower end of the rod, a star spring located in the groove and including a plurality of radially extending tongues engaging the inner faces of the jaws, and tending to 65 spread them apart, the annular reduced portion of the rod being adapted to engage the inner ends of the jaws and limit their spring actuated fulcruming movement on the shoulder.

OWEN J. WILLIAMS.
